US0D1030774S

(12) **United States Design Patent** (10) **Patent No.:** **US D1,030,774 S**
(45) **Date of Patent:** **** Jun. 11, 2024**

(54) **DISPLAY SCREEN WITH GRAPHICAL USER INTERFACE**

(71) Applicant: **HUAWEI TECHNOLOGIES CO., LTD.**, Shenzhen (CN)

(72) Inventors: **Yue Hu**, Suzhou (CN); **Zongwei Wang**, Beijing (CN); **Qing Zhuang**, Shenzhen (CN)

(73) Assignee: **HUAWEI TECHNOLOGIES CO., LTD.**, Shenzhen (CN)

(**) Term: **15 Years**

(21) Appl. No.: **29/752,672**

(22) Filed: **Sep. 28, 2020**

(30) **Foreign Application Priority Data**

Apr. 1, 2020 (CN) 202030120576.8

(57) **CLAIM**

The ornamental design for a display screen with graphical user interface, as shown and described.

DESCRIPTION

The single FIGURE is a front view of a display screen with graphical user interface, showing our new design.

The broken lines in the FIGURE show portions of the graphical user interface that form no part of the claimed design. The dot-dash broken-line perimeter illustrates a display screen and forms no part of the claimed design.

1 Claim, 1 Drawing Sheet
